UNITED STATES PATENT OFFICE.

JONAS G. JOHNSON, OF BALTIMORE, MARYLAND.

DESIGN FOR A FIREPLACE.

Application filed January 20, 1928. Serial No. 24,939. Term of patent 14 years.

To all whom it may concern:

Be it known that I, JONAS G. JOHNSON, a citizen of the United States, residing at the city of Baltimore and State of Maryland, have invented a new, original, and ornamental Design for a Fireplace, of which the following is a specification, reference being had to the accompanying drawing, forming part thereof.

Figure 1 is a front perspective view of a fireplace showing my new design; and Fig. 2 is a side elevation of the same on a reduced scale.

I claim:

The ornamental design for a fireplace as shown.

JONAS G. JOHNSON.
